PULL TOY

Bernard Albert, Petersburg, Va., assignor to James Industries, Inc., Paoli, Pa., a corporation of Pennsylvania

Application May 6, 1958, Serial No. 50,778

Term of patent 7 years

(Cl. D34—15)

FIG. 1.

FIG. 2.

FIG. 3.

FIG. 4.

Fig. 1 is a perspective view of a pull toy showing my new design;

Fig. 2 is a side elevational view, the opposite side having substantially the same appearance;

Fig. 3 is a plan view; and

Fig. 4 is a front elevational view.

I claim:

The ornamental design for a pull toy, as shown and described.
